Patented Mar. 8, 1921.

UNITED STATES PATENT OFFICE.

HENRY M. LAMBERT, OF PORTLAND, OREGON.

METHOD AND APPARATUS FOR MAKING BELTS.

1,370,597.

Specification of Letters Patent.

Patented Mar. 8, 1921.

Application filed December 24, 1919. Serial No. 347,093.

To all whom it may concern:

Be it known that I, HENRY M. LAMBERT, a citizen of the United States, at present residing at Portland, in the county of Multnomah and State of Oregon, have invented a new and Improved Method and Apparatus for Making Belts, of which the following is a specification.

My invention relates to the art of manufacturing stretchless belts and it particularly has for its object to provide a convenient and effective method and apparatus for manufacturing belts, which belts are constructed of alternate layers of rubberized fabric and cords.

In carrying out my invention, I simultaneously lay between spaced strips of rubberized fabric, a layer of cords extending in parallelism, the cords being either individual or held together by transversely woven light cords or strands, placing the cords under such tension as to stretch the same to their approximate limit of elongation, while being laid and vulcanizing the cords and fabric strips together, while under tension.

In its more detailed nature, the invention includes those novel steps of manufacture and the novel details of construction and arrangement of parts of the apparatus employed in carrying out the invention, all of which will be first fully described, then specifically pointed out in the appended claims, reference being had to the accompanying drawings, in which:

Figure 1 is a diagrammatic longitudinal section illustrating an arrangement of apparatus adapted to the performance of my method.

Fig. 2 is a detail view of a portion of the rubberized fabric strip.

Fig. 3 is a detail view of a portion of the series of parallel cords showing how they may be tied together by transversely woven threads.

In the drawings in which like numerals of reference indicate like parts in all of the figures, 1 represents the vulcanizing press which may be of the usual construction embodying a base or support that carries a suitable bed 2 to coöperate with the pressing head 3, the latter being designed to be pressed down toward the bed 2 by any suitable mechanism, as for instance, cam levers 4.

The bed 2 and head 3 may be chambered at 5 to provide steam jackets, whereby the

temperature of the parts may be maintained for vulcanizing purposes.

6 and 7 designate the rolls carrying rubberized fabric strips 8. 9 indicates an idler roller over which the lower strips pass. 10 designates the drum or reel from which the cords are taken.

It should be understood that when the cords are held together by transversely woven threads, one reel 10 is sufficient, when the cords are laid individually, a separate reel for each strand of cord may be employed.

The reels 10 carrying the cords are provided with suitable tension devices 11, whereby the cords may be held under maximum tension, while being laid.

12 designates the cords and 13 the transverse threads holding the cords together (when a cord series unit is used).

14 designates the take-up reel, which is driven by a worm and gear arrangement 15 of the ordinary type.

In practice, the lower layer of fabric 8 is passed over the roller 9, across the bed 2 and started on the reel 14. The cords 12 are then passed over the fabric strip 8, across the bed 2 and started on the reel 14, as is also the upper or top layer 8 of rubberized fabric.

This arrangement, it will be noted provides for laying the fabric layers 8 with the cords 12 between them and simultaneously winding the same on the take-up reel 14.

By adjusting the tension device 11, the drag on the reel 10 may be regulated so as to place the cords 12 under a stretch approximating their limit of elongation.

The head 3 is then lowered and the section of belting contained between the head 3 and bed 2 is vulcanized, after which the head 3 is raised, in any suitable manner, as for instance by springs 16, and the vulcanized section of belt wound on the reel 14, after which the next section is vulcanized in the same manner and so on until the desired length of belt has been produced.

As the chief strength of the belt is obtained by use of the cords and as the cords and fabric strips are vulcanized together while the cords are under tension, it will be seen that the process of vulcanization holds the cords in their elongated or stretched form and thus the belt as finally produced becomes in reality a stretchless belt.

Tension may also be applied to the rollers 6 and 7, if desired to stretch the fabric 8 in

its longitudinal direction but, of course, the degree of tension applied to the fabric strips 8 need only be sufficient to take up the slack in such strips during the laying process.

5 While I have shown an apparatus and described a process of manufacture producing a belt with but a single layer of cords, it is quite obvious that the number of cord layers and fabric strips may be increased as desired in order to make a belt of the proper 10 strength and size.

From the foregoing description taken in connection with the accompanying drawings, it is thought the invention will be clear 15 to those skilled in the art and I desire it understood that changes in the details may be made without departing from the spirit of the invention or the scope of the claims.

What I claim is:—

20 1. The method of manufacturing belts which consists in taking alternate layers of rubberized fabric and cords, laying a layer of cords between opposite layers of fabric strips and stretching the cords to their approximate limit of elongation, while being 25 laid, and vulcanizing the whole into a unitary mass, while said cords are held stretched.

2. The method of manufacturing belts 30 which consists in placing on a layer of rubberized fabric a layer of cords consisting of

a plurality of strands laid side by side in parallelism, placing over said cords another layer of rubberized fabric, stretching said cords to their approximate limit of elongation, holding the same stretched and vulcanizing the mass, while the cords are held stretched whereby, through the process of vulcanizing the parts, the parts will be united in an individual structure and the 40 cords maintained in their stretched condition.

3. An apparatus for manufacturing belts comprising a vulcanizing press, a take-up reel, a pair of feed reels adapted to contain 45 strips of fabric and a third feed reel adapted to contain cord strands, said reels being arranged to deliver the fabric and cord in alternate layers to the vulcanizing press, the said take-up reel being arranged to receive 50 the combined layers of fabric and cord from the vulcanizing press, means for turning the take-up reel, and means for retarding the feed of the cord carrying reel, whereby to place the cord under tension, as the layers 55 are passed through the vulcanizing press, whereby the mass may be vulcanized into a unitary structure, while the cord is held under tension, substantially as shown and described.

HENRY M. LAMBERT.
